UNITED STATES PATENT OFFICE.

JACOB J. MEAD, OF NEW YORK, N. Y. ASSIGNOR TO MEAD FOUNTAIN PEN CO., A CORPORATION OF NEW YORK.

FOUNTAIN-PEN.

No. 900,944.

Specification of Letters Patent. Patented Oct. 13, 1908.

Application filed November 2, 1907. Serial No. 400,413.

To all whom it may concern:

Be it known that I, JACOB J. MEAD, a citizen of the United States, residing at the borough of Brooklyn, in the city of New York, county of Kings, and State of New York, have invented certain new and useful Improvements in Fountain-Pens, of which the following is a specification, reference being had therein to the accompanying drawings, 10 which form a part thereof.

My invention relates to fountain pens, and more particularly to that class thereof known as self filling wherein means forming a part of the pen, are provided to draw ink into the pen barrel.

In the ordinary, well known style of fountain pen, to fill and refill same it is necessary to remove a screw threaded stopper for the barrel, and inject ink into said barrel, by means 20 of a compressible rubber bulb, and a filling tube attached thereto. This style of pen has the objection, that in filling and re-filling considerable inconvenience results, and the ink is passed directly to the barrel so that the ink 25 in the pen and in the feeder is allowed to remain undisturbed. In the type of self-filling pens now in use, it has been a general practice to avoid the inconvenience of the use of a separate filler, to place a compressible rubber 30 receptacle within the pen barrel, and in communication with the ink feeding attachments, and provide exteriorly exposed means whereby the receptacle may be compressed to expel ink or air therefrom, through the feeder 35 and pen and by immersing the pen and feeder in ink, draw ink through the same duct or ducts into this receptacle. This type of pen prevents the clogging of the pen point and of the feeder, but has the disadvantage that 40 flexible rubber will not retain its elasticity for any considerable time, and when exposed to the acids contained in inks, its ordinary life is materially shortened. A further disadvantage of this type is that the capacity of 45 the receptacle is small compared to the size of the barrel necessary to retain same.

The main object of my invention is to provide a fountain pen which may be emptied or filled through the ducts of the feeder, thus 50 preserving the advantages incident to the passage of ink through such ducts; and wherein the refilling means positioned within the barrel, may be made of non-flexible substance, thus preventing its being ren-

dered inoperative through repeated use, or 55 the action of the air or ink thereon.

A further object is to provide a pen of this character wherein the capacity of the barrel will not be materially diminished by the presence therein of the automatic filling 60 mechanism.

A still further object is to provide a pen of this character wherein the various parts will be so nested as to permit their being all contained within a barrel of ordinary length, 65 while being quickly brought into the operative position when it is desired to re-fill the pen, and restored to normal after it is filled, without expelling ink from the barrel.

A still further object is to provide a fountain pen wherein the ink or air may be expelled from the barrel and fresh ink drawn thereinto by means of a reciprocating piston contained within the barrel, in a manner to give the same appearance to the pen irrespective of the position of the plunger. And a still further object is to provide a self filling fountain pen of simple construction, which will be positive in its action in expelling ink and air from, and drawing ink into the barrel, 75 which will be simple and quick in its operation, and which cannot be readily gotten out of order.

The invention consists primarily in a fountain pen comprising a barrel, the combination with a feeder and a point, of a piston fitted to and mounted in said barrel, a stem whereby said piston may be reciprocated and means exposed exteriorly of the pen whereby said stem may be operated; and in such 85 other novel features of construction and combination of parts as are hereinafter set forth and described, and more particularly pointed out in the claims hereto appended.

Referring to the drawings: Figure 1 is a 95 side elevation of the pen with the operating handle drawn out preparatory to the expulsion of ink and air therefrom, the barrel being broken away to show the piston and piston stem. Fig. 2 is a detail view of the piston, and its stem, and the operating handle in cross section, and Fig. 3 is a cross section of the pen showing the various parts nested after the barrel is filled.

Like letters refer to like parts throughout 105 the several views.

In the embodiment of my invention shown in the accompanying drawings, a indicates a

pen barrel, *b* the pen point, *c* the feeder, and *d* the cap. The parts *b*, *c*, and *d*, may be of any desired construction and arrangement, my invention requiring merely a modification of the barrel to adapt it to the purposes of the invention. The cap *d* is vented in the usual and well known manner through the opening *d'*.

The barrel *a* differs from the ordinary fountain pen barrel in that it is open at both ends, at one end to receive the feeder *c*, and pen *b*, and at the other end to allow clearance for the operation of the refilling mechanism. The inside of this barrel is preferably cylindrical and finished to remove irregularities, a finish which may be imparted thereto in the molding process. Fitted to, and seated within said pen barrel, is a reciprocating piston or plunger *e*, which may be made of cork or other suitable material, which piston plunger is adapted to be reciprocated to expel ink or air from the barrel, or to create a vacuum therein, to draw fresh ink thereinto through the ducts in the feeder *c*.

The piston or plunger *e* carries centrally thereof a stem *f* having a straight longitudinal slot *f'* therein and lateral extensions *f''* adjacent to each end of said slot forming therewith one member of a bayonet joint.

Passing through the slot *f''* so as to act as a guide therefor, and as a stop for retaining the piston or plunger in the barrel and limiting the quantity of its movement in filling the pen, is a pin *g* the opposite ends of which pass through and are flush with the outer surface of the barrel *a*.

Mounted upon the stem *f* is an operating sleeve *h* the lower end *h'* of which conforms in dimensions to the bore of the barrel *a*, having a tight sliding fit therewith; and the top *h''* of which is finished so as to present a shoulder *h''* to the top of the barrel and have such outside dimensions as to conform to those of the barrel, and when the refilling mechanism is nested, have the appearance of being a part of said barrel. The outer end of said sleeve is shown as being open to provide a proper vent thereto and a separate vent *j* aligned with the slot *f'* is also provided, the said sleeve being of a length to cause the end of the stem *f* to come substantially flush with this end of the sleeve to close it, when the pen is filled, and the parts are restored to normal.

Adjacent to the lower end of the part *h'* of the sleeve *h*, is a pin *i* which passes through the slot *f* and is adapted to pass into the upper branch slots *f''*. The function of this pin *i* is not only to retain the sleeve in relation to the barrel, but to permit the sleeve to be moved to bring said pin into such relation to the slots *f''* as to permit the plunger *e* being operated thereby, but also to permit the said sleeve when the plunger is drawn out to the full extent, to be slid upon the stem *f* to nest the parts.

It will be observed that the construction heretofore described is such as to permit the various parts to be made of material which will not be materially affected by wear, or by acids in the ink, and that the various parts 70 may be inexpensively and accurately produced.

The operation of the herein described fountain pen is substantially as follows. The various parts being in the positions shown in Fig. 2, and it being desired to refill the pen, the part *h''* of the sleeve *h* exposed exteriorly of the pen, is used to draw the sleeve outwardly, the lower slots *f''* passing from the pin *g* and the pin *i* moving in the slot *f'* to 80 permit said movement. When the said sleeve *h* is drawn out to its full extent, as shown in Fig. 1, it is turned so as to cause the said pin *i* to pass into the upper slots *f''* thus locking said sleeve *h* in relation to the stem *f*. The sleeve *h* is then forced inward, carrying with it the stem *f* and the piston or plunger *e*, which latter will expel any ink, and all the air, remaining in the barrel *a*, such matter being expelled through the duct in 90 the feeder *c*, thus serving to cleanse the said feeder and the pen itself. The pen is then dipped in ink, so as to submerge the open end of the said duct of the feeder, and the sleeve *h* again drawn outwardly, this time bringing 95 the stem *f* and the piston or plunger *e* with it, thus creating a vacuum in the barrel *a* and causing ink to flow through the duct in the feeder, to said barrel. This restores the parts to the position shown in Fig. 1, the barrel *a*, 100 however, being filled with ink. During this process, the pin *g* prevents the stem *f* and the plunger *e* from turning, thus guiding its movement, and also brings the parts to a stop at the proper point to not only prevent the entire withdrawal of the piston or plunger *e*, but also position these parts so as to permit the nesting thereof in a manner to preserve the neat appearance of the pen. The pen having been filled as described, the sleeve *h* is 110 turned in the opposite direction disengaging the pin *i* from the slots *f''*, and bringing it into alignment with the slot *f'*. The said sleeve *h* is then again pressed inwardly, the pin *i* moving in the slot *f'*, thus causing the sleeve to 115 move upon the stem *f* having no effect upon the plunger *e*. The part *h'* being of substantially the same dimensions as the inner dimensions of the barrel *a*, enters same with a sufficiently tight fit to hold the entire sleeve 120 *h* firmly; and the upper part of the stem *f* is permitted to pass into the said sleeve, any air therein being discharged from the open top thereof and the air between the piston and the barrel top discharging through the 125 vent *j*. The top of the stem is so finished that when it comes substantially flush with the end of said sleeve, it serves to close it and give a neat finish thereto. The plunger *e* being a fairly tight fit, the ink is not permitted 130

to escape around same, from that part of the barrel between said plunger and the feeder. While the space is not as great as in the ordinary fountain pen, nevertheless, the gain in 5 the diameter of the bore is sufficient to materially increase the capacity over that of self filling pen wherein a separate receptacle for the ink is seated within the barrel.

It will be observed that in a pen constructed as described, the screw threaded connection between the removable end of the barrel containing the pen and feeder, and the barrel proper, is dispensed with, thus avoiding the difficulties attendant upon securing a 10 good, ink tight joint at this point. The plunger e , end h^1 and head h^2 give an ample packing to the only joint through which ink could escape, there being no screw joints in the entire device. It will also be observed that 15 20 with the direct reciprocating movement of the piston or plunger e , the pen may be quickly refilled.

I am aware that self filling fountain pens are now in use, and I do not intend to claim 25 such a device broadly, I believe, however, that by providing and arranging all the parts substantially as herein shown and described, new and useful results are attained.

While I have shown a construction of pen 30 which has been found in use to have satisfactory results, I do not, nevertheless, wish to limit the invention to the precise details of construction shown in the drawings, such being capable of variation to adapt the mechanisms to different types and styles of pens, which would come within the spirit and 35 scope of the invention.

Having described the invention, what I 40 claim as new and desire to have protected by Letters Patent is:—

1. In a fountain pen, the combination with a barrel, a feeder and a point, of a piston fitted to and mounted in said barrel, a stem having a longitudinal slot therein and branch 45 slots forming therewith a part of a bayonet joint, whereby said piston may be reciprocated, and a sleeve carrying a pin seated in said longitudinal slot and adapted to enter said branch slots, mounted on said stem and 50 exposed exteriorly of the pen, whereby said sleeve may be reciprocated with said stem or independently thereof.

2. In a fountain pen, the combination with a barrel, a feeder and a point, of a piston 55 fitted to and mounted in said barrel, a stem having a longitudinal slot therein and branch slots forming therewith a part of a bayonet joint, whereby said piston may be reciprocated, a pin passing through said slot and 60 carried by said barrel whereby said stem is guided, and the extent of its reciprocation is limited, and a sleeve carrying a pin seated in said longitudinal slot, and adapted to enter said branch slots, mounted on said sleeve and

exposed exteriorly of the pen whereby said 65 sleeve may be reciprocated with said stem or independently thereof.

3. In a fountain pen, the combination of a barrel, a feeder and a point, of a piston fitted to and mounted in said barrel, a stem having 70 a longitudinal slot therein, and branch slots forming therewith a part of a bayonet joint, whereby said piston may be reciprocated, a sleeve mounted on said stem comprising one 75 part of substantially the same dimensions as the bore of said barrel and an enlarged head, whereby a shoulder adapted to engage the end of said barrel is formed, and a pin carried by said sleeve and passing through said slot, whereby said sleeve is capable of being 80 reciprocated with said stem or independently thereof.

4. In a fountain pen, the combination with a barrel, a feeder and a point, of a piston fitted to and mounted in said barrel, a stem 85 having a longitudinal slot therein, and branch slots forming therewith a part of a bayonet joint, whereby said piston may be reciprocated, a pin passing through said slot and carried by said barrel, whereby said stem 90 is guided and the extent of its reciprocation is limited, a sleeve mounted on said stem comprising one part of substantially the same dimensions as the bore of said barrel, and an enlarged head, whereby a shoulder 95 adapted to engage the end of said barrel is formed, and a pin carried by said sleeve and passing through said slot, whereby said sleeve may be reciprocated with said stem or independently thereof.

5. In a fountain pen, the combination with a barrel, a feeder and a point, of a piston fitted to and mounted in said barrel, a stem having a longitudinal slot therein and branch 100 slots forming therewith a part of a bayonet joint, whereby said piston may be reciprocated, a pin passing through said slot and carried by said barrel whereby said stem is guided and the extent of its reciprocation is limited, a sleeve having its outer end open 105 and adapted when the pen is filled to be substantially flush with the end of said stem, mounted on said stem, comprising one part of substantially the same dimensions as the bore of said barrel, and an enlarged head, 110 whereby a shoulder adapted to engage the end of said barrel is formed, and a pin carried by said sleeve and passing through said slot, whereby said sleeve may be reciprocated with said stem or independently thereof.

In witness whereof I have hereunto affixed my signature this 25th day of October, 1907, in the presence of two witnesses.

JACOB J. MEAD.
